UNITED STATES PATENT OFFICE.

WALTER R. SUTHERLAND, OF SALEM, MASSACHUSETTS, ASSIGNOR OF ONE-FOURTH TO EDWIN COOK AND ONE-FOURTH TO CHARLES A. COOK, BOTH OF DANVERS, MASSACHUSETTS.

MACHINE FOR APPLYING TOGGLES TO SKINS.

1,138,328.

Specification of Letters Patent.

Patented May 4, 1915.

Application filed May 15, 1914. Serial No. 838,868.

To all whom it may concern:

Be it known that I, WALTER R. SUTHERLAND, a citizen of the United States, residing at Salem, county of Essex, State of Massachusetts, have invented a certain new and useful Improvement in Machines for Applying Toggles to Skins and the like, of which the following is a specification, reference being had therein to the accompanying drawings.

In the manufacture of leather it is customary to stretch the skins on boards or frames for the purpose of drying the leather, and it is desirable that during this process the skins shall be stretched as much as possible in order that the measurement of the completed product shall be the greatest possible. Two methods of holding the skins during the drying operation have been employed in the past. In the first method, a flat board is employed on which the skin is stretched and tacked. This has the disadvantage that the skins dry slowly owing to the fact that they lie in contact with the board; also that the workman cannot stretch the skin to the fullest extent. Furthermore, the margin of the skin is injured by the tack holes and is usually trimmed off, resulting in waste. In the second method, a frame is employed to which the skin is secured by toggles which consist of a metallic clamp and a piece of string of suitable length. The clamp is snapped onto the edge of the leather and the skin is stretched onto the frame, the string being secured to hooks located on the frame. This method has the advantage of producing a considerable increase in the measurement of the skin and in not injuring the margin of the skin, and in permitting the skin to dry much more rapidly since it is exposed freely to the air on both sides. Also, when frames are used, a smaller dry room may be employed for the same amount of product. This method, however, has the serious disadvantage that it takes very much more time to apply the toggles to the edge of the skin than it does to tack the skin on boards, and is therefore uneconomical so far as labor is concerned. Heretofore so far as known to me, the toggles have always been applied to the skin by hand, and this hand-operation involves straightening out the strings, opening the toggles and then forcibly closing the toggle on the skin. If

the skin is unusually thick, difficulty may be experienced by the operator in closing the toggle, it being necessary to press the handle or lever of the toggle against some unyielding surface, as for instance, the bench.

My present invention has for its object to provide a machine by which the toggles may be rapidly secured to the skins, and forcibly closed regardless of the thickness of the skin, and with such speed that the entire operation of stretching the skin on the frame occupies less time than has heretofore been employed in tacking the skin onto drying boards. The use of my machine, therefore, makes it possible to obtain the advantages resulting from the use of toggles and drying frames, while the labor expense of so doing is reduced to at least that of the old method of tacking the skins onto drying boards.

The invention will be fully understood by reference to the following description taken in connection with the accompanying drawings, and the novel features thereof are pointed out and clearly defined in the claims at the close of this specification.

In the drawings, Figure 1 is a front elevation of a machine embodying my invention. Fig. 2 is a side view of the machine shown in Fig. 1, the lower portion of the frame being broken away. Fig. 3 is a view similar to Fig. 2, but showing the parts in the position which they occupy after the toggle has been closed. Fig. 4 is a section of the raceway on line 4—4 Fig. 1. Fig. 5 is a view showing the toggle of one well known construction adapted to be clamped onto the edge of the skin by the use of the machine which forms the subject of the present invention.

Referring to the drawings, at 11 is shown the frame of the machine on which the working parts are supported. At 12 is shown the raceway, preferably composed of two moldings 13 and 14 of wood or other suitable material, separated by a suitable space and supported at the lower end by the bracket 15, see Figs. 2 and 3, and held together at intervals by other brackets 15. The space between the two moldings is of such a shape (see Fig. 4) as to permit a series of toggles to be placed therein and to slide sidewise down the raceway. The lowest toggle in place in the raceway is shown at A in Fig. 2. The raceway is curved upwardly and is prefer-

ably extended through the ceiling to the room above so that the toggles may be inserted there and also that the weight of the toggles in the raceway will be sufficient to feed them forward as the lowest toggle is removed from the machine upon being secured to the edge of the skin. While I have shown a gravity feed for the toggles, I do not limit myself to this construction.

10 The toggles A are inserted in the raceway with the lever *a* hanging down so that the jaws of the toggles are separated ready for the reception of the edge of the skin. At 16 is shown a lever pivoted at 17 to the 15 frame of the machine, and provided at 18 with a finger to engage the lever *a* of the lowest toggle A. The said lever 16 is actuated by the rod 19 operated by a treadle 20 pivoted at 21 to the frame of the machine. 20 The said lever 16 is held normally in its lowest position by means of a spring 22 engaging a collar 23 secured to the rod 19. It will therefore be seen that when the operator presses his foot on the treadle 20 the 25 toggle actuating finger 18 raises up the lever *a* of the toggle A and forcibly compresses the jaws of the toggle onto the skin. The moldings 13 and 14 are cut away at 24 to give room for the removal of the toggle 30 after it has been snapped onto the skin, and also to allow the finger 18 to raise up the lever *a* and close the toggle. For the purpose of supporting the toggle during the operation, I provide a flat spring 25 which 35 bears against the under side of the toggle so that the toggle is held between it and the underside of the top molding 13. The spring 25 is not of sufficient thickness to interfere with the closing of the toggle when 40 the finger 18 is raised. The wall 26 opposite the end of the raceway 12 acts as a stop so that the lowest toggle is properly positioned to be operated upon by the finger 18.

45 The operation of my machine is as follows: As previously explained, the toggles with the strings attached are placed in the raceway in sufficient numbers so that the weight of the toggles in the inclined portion will cause the toggles occupying the horizontal portion of the raceway to be fed forward. The operator then presents the edge of the skin to the jaws of the lowermost toggle A and depresses the treadle 20. 50 This raises the toggle engaging finger 18 and clamps the toggle forcibly upon the skin. The toggle which is now firmly attached to the edge of the skin is then withdrawn from the machine by the skin and the 55 string which is attached to the toggle is drawn out with it. When the operator releases the treadle, the finger 18 falls to its 60 normal position and immediately another 65

toggle is pushed into place by the pressure of the other toggles in the raceway.

It will be seen from the foregoing that the toggles may be clamped onto the edge of the skin just as fast as the operator can present the skin at different points to the machine. It will also be seen that no exertion on the part 70 of the operator is required to close the toggle and that the toggle is firmly clamped onto the edge of the skin.

The machine rapidly attaches the toggles to the skins and makes it possible to use toggles with their attendant advantages without a prohibitive labor expense.

What I claim is:

1. In a machine of the character described, the combination of a raceway capable of 80 supporting a series of toggles and having a longitudinal slot through which the string on the toggle hangs out and a finger to engage the lever of the toggle and forcibly close the toggle onto the skin.

2. In a machine of the character described, the combination of a raceway of a cross-section adapted to receive a series of toggles placed side by side and having a longitudinal slot through which the string on the toggle hangs out, a finger to engage the lever of the toggle and forcibly close the toggle on the skin, and a pedal to operate said finger.

3. In a machine of the character described, the combination of a raceway composed of 95 two suitable moldings separated by a space adapted to receive a series of toggles with the levers of the said toggles in open position, said molding being cut away for a width equal to the width of one toggle to 100 permit the lever of the toggle to be swung to closed position, and a finger engaging the said toggle lever to move the said toggle lever through said cut-away space and close the toggle.

4. In a machine of the character described, the combination of a raceway composed of two suitable moldings separated by a space adapted to receive a series of toggles with the levers of said toggles in open position, 110 said molding being cut away for a width equal to the width of one toggle to permit the lever of the toggle to be swung to closed position, a thin member bridging said cut-away space and adapted to engage the underside of the body of the toggle, and a finger engaging the said toggle lever to move it through said cut away space and close the toggle.

In testimony whereof I affix my signature, in presence of two witnesses.

WALTER R. SUTHERLAND.
